FOLDING IRONING BOARD

Filed Feb. 7, 1938

UNITED STATES PATENT OFFICE

2,175,734

FOLDING IRONING BOARD

William A. Snyder, Los Angeles, Calif.

Application February 7, 1938, Serial No. 189,024

1 Claim. (Cl. 38—139)

My invention relates to a folding ironing board and has for its principal objects, to generally improve upon and simplify the construction of the existing forms of folding ironing boards and, to 5 provide a structure that includes a pair of ironing board members hinged to each other and one of said members capable of being swung downward with respect to the other member, so as to lower one end of the complete ironing board 10 in order to enable persons of short stature to more conveniently use the ironing board.

Other objects of my invention are to provide an ironing board, that is relatively simple in construction, inexpensive of manufacture and the 15 bracing of the ironing board being such as to provide a very strong, substantial and rigid support that will withstand the strains and stresses developed during ironing operations, and said ironing board having a folding extension that is 20 adapted to provide a support for the work after the same has been ironed on the main portion of the ironing board.

With the foregoing and other objects in view my invention consists in certain novel features 25 of construction and arrangements of parts that will be hereinafter more fully described and claimed and illustrated in the accompanying drawing in which:

Fig. 1 is a side elevational view of the structure 30 that is utilized as a folding ironing board.

Fig. 2 is a view taken on the line 2—2 of Fig. 1, and looking against the under side of the ironing board.

Fig. 3 is an enlarged detail section of a portion 35 of a rack that is positioned on the under side of the ironing board, and which serves as an adjustable bearing for the upper portion of one of the braces of the ironing board.

Fig. 4 is an elevational view looking in the direction indicated by the arrow 4 in Fig. 1.

Fig. 5 is a detail section taken on the line 5—5 of Fig. 1.

Fig. 6 is an enlarged cross-section taken on the line 6—6 of Fig. 5.

Referring by numerals to the accompanying drawing, 10 designates an ironing board preferably formed from a single piece of wood, one end of which is tapered and rounded as designated by 11, thus giving the board 10 the shape of an 45 conventional ironing board, and suitably secured to the under face of the board adjacent the end opposite the tapered and rounded end is a transverse cleat 12.

A board 13 that is equal in width to and considerably shorter than the board 10, functions as

a support or table to receive the work after the same has been done on the table 10, and arranged on the under side of the inner end of this table member 13 is a transversely disposed cleat 14 similar to cleat 12.

Arranged on the under sides of the cleats 12 and 14 adjacent their ends are hinges 15 which enables the outer ends of the boards 10 and 13 to be swung downwardly toward each other.

Connected by hinges 16 to the ends of the 10 cleat 12 are the upper ends of a pair of ironing board supporting legs 17 which, while in service, occupy an inclined position beneath the board 10 as illustrated in Fig. 1.

The intermediate portions of these legs 17 are 15 stayed and reinforced by crossed braces 18, preferably metal straps or rods. Suitably secured to the under face of board 10 a short distance inwardly from its rounded end 11 is a transversely disposed cleat 19, and secured to the under face 20 thereof is one end of a rod 20, the opposite end thereof being secured to the under side of the central portion of cleat 12. Thus rod 20 occupies a position parallel with and spaced a short distance below the under side of board 10. 25

Suitably secured to the under side of board 10 between the cleats 12 and 19 is a plate 21 preferably of sheet metal, and stamped therefrom are downwardly projecting lips 22 that function as stops and bearings for the horizontally disposed upper portion of an inverted U-shaped brace 23, the lower ends of the vertical legs of which are pivotally mounted on the lower portions of the legs 17.

When the ironing board is in use, the trans- 35 verse upper portion of the brace 23 bears against the inner edge of the cleat 19, thus holding the ironing board 10 level; and when the upper end of the brace is swung inwardly against the legs 17, the latter may be swung upwardly against 40 the under side of the ironing board.

In order to lower the outer end of the ironing board several inches in order to permit the ironing operations to be conveniently accomplished by persons of short stature, the upper end 45 of brace 23 may be swung inwardly toward the upper ends of legs 17 and engaged against one of the transverse lips 22 that project downwardly from plate 21. As a result of this arrangement, the outer end of the ironing board may be low- 50 ered a considerable distance, as illustrated by dotted lines in Fig. 1, and said board is firmly retained in such lowered position by the engagement of the upper end of brace 23 against one of the lips 22.

Connected by hinges 23 to the under side of the ends of cleat 14 are the upper ends of legs 24 which, when the ironing board is in use, occupy inclined positions beneath the board 13, as illustrated by dotted lines in Fig. 1. These legs are stayed and reinforced by crossed braces 25, preferably straps or rods of metal.

Pivotedly connected to the lower portions of legs 24 are the lower ends of the vertical legs of an inverted U-shaped brace member 26, and pivotedly connected by means of rivets 27 or the like to the upper portions of the vertical legs of said member 26 are the lower curved ends of brace members 28. The upper ends of members 28 are pivotedly connected to brackets 29 that are secured to the under side of a cleat 30, and the latter being suitably secured on the under side of board 13 a short distance inwardly from its outer end.

The braces 26 and 28 just described provide means for firmly maintaining the board 13 in horizontal position and in alignment with the ironing board 10 while the same is in use, and thus the board 13 provides a convenient table and support for the work that has been ironed.

Inasmuch as the pivot points 27 between the lower ends of base members 28 and upper portion of brace member 26 are located below the transverse upper member of the brace 26, the pivot points 27 move slightly past center when the braces are shifted into open or bracing position, and thus the table 13 is firmly supported while in service.

If desired, brace members such as 26 and 28 may be used between the lower portions of the legs 17 and the ironing board 10, and likewise the single brace member 23 may be used in the place of the brace members 26 and 28 between the legs 24 and board 13.

The outer ends of folding braces 31 are pivotedly connected to the upper portions of legs 17, and the inner ends of said braces are pivotedly connected at 32 to the inner ends of similar folding braces 33, the outer ends of which are pivotedly connected to the upper portions of legs 24. These braces, when open, maintain the legs 17 and 24 in proper position to support the ironing

board and table member 13 in a horizontal position, and when the pivotally connected ends of said braces are swung upward, the legs 17 and 24 are permitted to swing or fold toward each other.

Formed on the ends of brace members 31 beyond the pivot points 32 are hooks 34 that engage over the upper edges of brace members 33, thus preventing the pivotally connected ends of said brace members from passing downwardly "below center."

Thus it will be seen that I have provided a folding ironing board that is relatively simple in construction, inexpensive of manufacture and very effective in performing the functions for which it is intended.

It will be understood that minor changes in the size, form and construction of the various parts of my improved folding ironing board, may be made and substituted for those herein shown and described without departing from the spirit of my invention, the scope of which is set forth in the appended claim.

I claim as my invention:

An ironing board formed in two parts arranged so that their inner ends abut each other, one of which parts is approximately twice the length of the other part, cleats secured to the under faces of the two parts of the ironing board adjacent their abutting ends, hinges connecting said cleats, a pair of legs arranged beneath the longer part of the board, hinges connecting the upper ends of said legs to the cleat that is applied to the inner end of the longer part of the board, a brace hinged to the lower portions of said legs, a ratchet plate applied to the intermediate portion of the under side of the longer part of the ironing board for receiving and holding the brace in differently adjusted positions and thereby support the longer member of the ironing board in different inclined positions, means applied to the under side of the longer part of the ironing board for limiting the swinging movement of said brace in both directions and means including folding leg and braces for supporting the shorter part of the board.

WILLIAM A. SNYDER.
